UNITED STATES PATENT OFFICE.

HENRY W. HIRSCHFELD, OF MERIDEN, CONNECTICUT, ASSIGNOR TO THE
MERIDEN BRITANNIA COMPANY, OF SAME PLACE.

DESIGN FOR A SPOON AND FORK HANDLE.

SPECIFICATION forming part of Design No. 16,713, dated June 1, 1886.

Application filed April 26, 1886. Serial No. 200,250. Term of patent 14 years.

To all whom it may concern:

Be it known that I, HENRY W. HIRSCHFELD, of Meriden, in the county of New Haven and State of Connecticut, have invented new 5 Designs for Spoon and Fork Handles; and I do hereby declare the following, when taken in connection with the accompanying drawing and the letters of reference marked thereon, to be a full, clear, and exact description of 10 the same, and which said drawing constitutes part of this specification, and represents a face view.

This invention relates to a design for the handles of spoons, forks, and like articles of 15 table service; and it consists in the ornamentation of the surface of the handle, as hereinafter described, and shown in the accompanying illustration. The body or bowl constitutes no 20 part of the invention, and this is illustrated as broken away. From the body the handle extends in the form of a narrow shank, A, the surface of which is ornamented by a series of 25 diagonal convex ribs extending from side to side. At the termination of the shank, or where the widening of the handle practically commences, a transverse rib, a, is formed. Above this rib a panel is formed by a narrow

margin extending around the edge of the handle, and about midway of the length of this panel an upwardly curved bar, b, extends 30 from the margin at one side to the margin at the opposite side. On the surface of the panel, below the bar b, is a tracery of palms and scroll-work. Above the bar b, on the panel, is the representation of a human head with a crown-like ornament that extends to the margin, as 35 shown in the accompanying illustration.

I claim—

The design for spoon and fork handle, consisting of the shank A, having its surface 40 ornamented by a series of diagonal convex ribs, with a transverse rib, a, above, and a handle above the rib, having a narrow border around its edge, forming a panel, and the panel divided by a curved bar, b, the surface of the 45 panel below the bar ornamented with a tracery of palms and scroll-work, and the panel above the bar representing a human head, as described, and shown in the accompanying illustration.

HENRY W. HIRSCHFELD.
